DESIGN FOR A DISPLAY BOX

Elizabeth N. Graham, New York, N. Y.

Application May 2, 1947, Serial No. 138,782

Term of patent 14 years

(Cl. D80—5)

To all whom it may concern:

Be it known that I, Elizabeth N. Graham, a citizen of the United States of America, residing in New York city, county of New York, and State of New York, have invented a new, original, and ornamental Design for a Display Box, of which the following is a specification, reference being had to the accompanying drawing, forming part thereof, wherein,

Figure 1 is a top plan view of a display box, showing my new design.

Figure 2 is an end elevational view, and

Figure 3 is a front elevational view of the display box shown in Figures 1 and 2.

I claim:

The ornamental design for a display box, substantially as shown.

ELIZABETH N. GRAHAM.
